UNITED STATES PATENT OFFICE.

UMBERTINO UMBERTO, OF OTTAWA, ILLINOIS.

MOTOR-CYCLE COURSE-INDICATOR.

1,268,645.

Specification of Letters Patent. Patented June 4, 1918.

Application filed July 7, 1917. Serial No. 179,157.

To all whom it may concern:

Be it known that I, UMBERTINO UMBERTO, a subject of the King of Italy, and resident of Ottawa, in the county of La Salle and 5 State of Illinois, have invented certain new and useful Improvements in Motor-Cycle Course-Indicators, of which the following is a specification.

This invention relates to traffic signals 10 and has more especial reference to an improved motorcycle course indicator.

The invention has for its dominant object to provide a signal means especially adapted for use on motorcycles, whereby, the 15 course of the same will be automatically signaled to following vehicles or pedestrians, allowing them to act accordingly.

It is a more specific object of the invention to provide means for automatically operating the signal upon the changing of the course of the motorcycle or upon the stopping thereof, the said means compressing air and directing it onto the signal, thereby operating the same.

25 It is also an object of the invention to provide novel form of signal, the same including a slidable display plate having indicating matter arranged thereon, which matter is normally concealed but which in the event 30 of the changing of the course of the motorcycle or the stopping thereof will be automatically moved to its closed or displaying position.

Other independent objects are to provide 35 features of construction of portions of the device which tend toward the attainment of the above aims irrespective of the relation in which they are used.

Other objects will be in part obvious and 40 in part pointed out hereinafter.

The invention accordingly consists in the features of construction, combination of elements and arrangement of parts which will be exemplified in the construction herein- 45 after set forth, and the scope of the application of which will be indicated in the following claims.

In the accompanying drawings, wherein is shown one of various possible embodiments of my invention;

Figure 1 is a top plan of the improved signal operating means;

Fig. 2 is a fragmentary longitudinal section therethrough;

55 Fig. 3 is a fragmentary detail in section of one of the telescopic connecting rods;

Fig. 4 is a detail in perspective of the piston cross head of the air compressing means;

Fig. 5 is a front elevation of the improved signal;

Fig. 6 is a horizontal section therethrough; and

Fig. 7 is a fragmentary detail in section showing the connection of the operating means with the indicator matter bearing 65 sign of the signal.

Similar reference characters refer to similar parts throughout the several views of the drawings.

Certain features and aims of this invention will be more readily understood if the following facts be borne in mind: As

is well known the traffic regulations of practically all cities require that the drivers of vehicles, preparatory to the changing of 75 their course or the stopping of their vehicles display some type of signal whereby following vehicles and pedestrians will be informed thereof and as a consequence will be enabled to travel safely. To comply with 80 these regulations, the drivers of vehicles, when about to change the course or stop the same raise their hands, thus, indicating to the traffic that a change in their course is about to be made. As will be appreciated, 85 the drivers of vehicles upon raising their hands to signaling position partially release the controlling means of the same thus rendering the operation exceedingly dangerous. The eliminating of the above outlined 90 disadvantages are among the dominant aims of this invention, and are, among others, attained in construction of the nature of that hereinafter described.

Referring now more specifically to the 95 several figures of the drawings there is pro-

vided a signaling means comprising a cas- 100 ing or housing designated 1, the forward portion of which is substantially rectangular in shape and is flanged as at 2. Within this flanged portion 2 a plate 3 having a plurality of spaced openings 4 formed 105 therein is arranged, while directly behind the same a slidable transparent sign 5 is positioned, the said sign being received within

suitable guide ways formed by transversely extending ribs 6 formed upon the adjacent portions of the top and bottoms of the casing 1. Matter such as the word "Stop" is printed upon the transparent sign or casing 110 5, the lettering thereof being spaced to permit its display through the openings 4.

formed in the rectangular plate 3 when moved to its operative position.

To the rear extremity of the casing 1 there is secured a cylinder 7, the said cylinder being fastened therein by means of a metal strap 8 passing thereabout and having its opposite ends engaged in suitable slits formed in the top of the casing 1, and also, by the arranging of the outer end of the 10 said cylinder through an opening formed in the reduced rear wall of the said casing. A piston 9 having a rod 10 is slidably arranged within the cylinder 7 and is normally held in a position adjacent its outermost extremity by means of an expansible coiled spring 11, while the free end of the 15 rod 10 is pivotally connected to a bell crank lever 12 mounted within the casing 1 as at 13. A slot 14 is formed in the free extremity of the bell crank lever and slidably receives therethrough a pin 15 carried upon a lug 16 which is affixed in some suitable manner to the transparent sign or pane 5. An inlet opening is formed within the head 20 of the cylinder 7 and receives therein one end of a compressed air supplying conduit 17.

Obviously, upon reciprocation of the piston 9 sliding movement will be imparted to the transparent sign or pane 5, thereby moving the descriptive matter thereon into and out of engagement with the opening formed in the plate 3.

With a view toward providing means 35 for operating the improved sign I employ an air compressing pump including a cylinder 18 having a removable hood 19 which carries upon its peripheral edge a guide bracket 20. In addition to carrying the 40 guide bracket 20, the removable cylinder head 19 also carries a plurality of horizontally aligned laterally extending semi-circular guide elements 21, the outer ends of which are engaged with a circular head 22 having a peripheral groove whereby a strap 23 45 may be disposed thereabout for securing the same to the frame of a motorcycle. A second strap 24 is passed about the cylinder 18 and is also adapted to engage the frame 50 of a motor cycle whereby the same may be securely attached thereto.

Slidably arranged within the pump cylinder 18 is a piston 25 having a rod 26, the outer end of which is engaged with a cross head 27 having its opposite ends curved and slidably arranged within the guide element 21. A screw threaded socket 28 is also carried by the cross head 27 and serves for a purpose which will be subsequently 60 apparent.

To normally maintain the piston 25 in a position adjacent the removable cylinder head 19 an expansible coiled spring 29 is arranged within the cylinder and has bearings thereon.

The discharge opening or port formed in the cylinder 18 receives the opposite extremity of the compressed air supplying conduit 17 therein.

Telescopic connecting rods 30 having looped ends 31 and 32 are provided, the looped ends 31 being arranged about a pivot screw 33 which is turned into engagement with the screw threaded socket 28 formed on the cross head 27, while the looped ends 32 are pivotally engaged with the handle bars or other steering gear of the motorcycle.

An angle arm 34 having a looped end 35 is also arranged about the pivot screw 33 while its remaining end is attached to the usual clutch shifting lever 36 through the medium of a link 37, the intermediate portion of said arm passing through the guide bracket 20 formed on the cylinder head 19.

In operation, during the travel of the motorcycle and upon the changing of the course thereof, the handle bars or other steering gear of the same will of course be turned and such movement will, obviously, 90 impart sliding motion to the piston 25 through the medium of the telescopic connecting rods 30 and the piston rod 26, thereby compressing air and forcing the same through the discharge conduit 17 into 95 the cylinder 7 against the piston 9 whereupon it will serve to reciprocate said piston and as a consequence slide the descriptive matter arranged on the pane 5 into alignment with the opening 4. As the machine 100 is again righted, that is, assume a straight away course, the connecting rods 30 will be returned to their normal positions, thus allowing the return of the pistons 9 and 25 through the medium of their respective 105 cylinders 7 and 18 to positions adjacent their cylinder heads. Thus, the descriptive matter on the pane 5 will be concealed by the solid portion of the plate 3. Should the operator of the motorcycle desire to stop, 110 he moves the clutch operating lever 36 in a direction to disengage the clutch from the power transmission gear and thereby causes the piston 25 to be again moved within its respective cylinder 18 to compress air, which 115 air is then forced through the conduit 17 into the cylinder 7 whereat the same serves to actuate the signal means in the manner as hereinbefore described. When the clutch operating lever is moved into engaging position, 120 the piston 25 will be then permitted to return to its normal position. However, in this connection it will be appreciated that should the motorcycle stand for a lengthy period of time the air within the cylinder 125 7 would be gradually exhausted and thus permit its respective piston 9 to assume normal position. By so doing the slidable sign 5 would be moved to its inoperative position.

Manifestly, the construction shown is capable of considerable modification and such modification as is within the scope of my claims, I consider within the spirit of my invention.

I claim:

1. In a device of the character described, the combination with the steering gear of a motorcycle of a signal arranged thereon, air compressing means communicating said signal, and means connected with the steering gear and the piston of said air compressing means for imparting motion thereto.
2. In a device of the character described, the combination with the clutch lever and steering gear of a motorcycle, of a signal arranged thereon, air compressing means communicating with said signal, means connected with the steering gear and the piston of said air compressing means for imparting motion thereto, and other means connected with said clutch lever and the piston of the air compressing means for operating the same independently of the steering gear.
3. In a device of the character described, the combination with the steering gear of a motorcycle, of an air compressing pump arranged thereon, a piston working within said pump, telescopic connecting rods pivotally engaged with the piston and the steering gear, a signal and air conducting means communicating with the air com-

pressing pump and said signal for operating the same.

4. In a device of the character described, the combination with the steering gear of a motorcycle, an air compressing pump arranged on the motorcycle, laterally extending guides carried by said pump, a cross head secured to the piston rod of the pump 40 slidable in said guide, telescopic connecting rods pivotally engaged with the cross head and the steering gear, a signal, and air conducting means communicating with the pump and said signal for operating the 45 same.

5. In a device of the character described, the combination with the clutch lever and steering gear of a motorcycle, of an air compressing pump arranged on the motorcycle, 50 a plurality of laterally extending guides carried by the pump, a cross head secured to the piston of the pump slidable within said guide, telescopic connecting rods pivotally engaged with said cross head and the 55 steering gear, an angle arm engaged with the clutch lever and having pivotal connection with said cross head, a signal, and air conducting means communicating with the pump and signal for operating same. 60

In testimony whereof I affix my signature hereto.

UMBERTINO UMBERTO.
